CAR TRUCK

Robert B. Cottrell, Chicago, Ill., assignor to
 American Steel Foundries, Chicago, Ill., a corporation of New Jersey

Application November 6, 1941, Serial No. 418,006

27 Claims.

(Cl. 105—197)

My invention relates to a railway car truck and especially to a type of truck commonly used in freight cars with spaced truss type side frames and a connecting bolster or load carrying member.

A general object of my invention is to devise an improved form of a well-known type of quick wheel change truck especially adapted for use in high speed service.

A specific object of my invention is to devise a practical form of high speed truck of quick wheel change type wherein each side frame is afforded bolster guide means centrally of the columns, and the ends of the bolster are formed with shelf portions which may engage with the columns as well as with an interlocking member which likewise engages said columns.

My invention also comprehends such an arrangement as that just described wherein the column engaging surfaces of the interlocking member and of the bolster ends are similar so that each may engage the same complementary surfaces on the guide columns.

A different object of my invention is to devise a freight car truck of the above general type wherein the interlocking member may have integrally formed therewith a housing with spaced friction walls into engagement with which may be resiliently urged friction shoes for slideable cooperation therewith.

My novel arrangement may further comprehend such a structure as that above set forth wherein the friction shoes for cooperation with the friction surfaces on the interlocking member may be conveniently and removably supported from the tension member of the side frame.

In the drawings, Figure 1 is a fragmentary side elevation of a railway car truck embodying my invention, only one end portion of the side frame being illustrated inasmuch as the structure is similar at opposite ends.

Figure 2 is a fragmentary top plan view of the truck structure shown in Figure 1, and Figure 3 is a fragmentary sectional view thereof, the section being taken in the vertical plane bisecting the truck transversely and as indicated by the line 3—3 of Figure 1.

Figure 4 is a further transverse sectional view taken in the vertical plane indicated by the line 4—4 of Figure 1, said section being taken approximately through the middle of one of the friction devices.

Figure 5 is a sectional view in the horizontal plane through the spring group and a portion of

the side frame taken substantially in the plane indicated by the line 5—5 of Figure 1.

Figures 6 and 7 show the detail of my novel form of interlocking member, Figure 6 being a half top plan, and Figure 7 a half side elevation thereof.

Figures 8, 9, and 10 show a modified form of my novel truck arrangement, Figure 8 being a fragmentary longitudinal vertical sectional view 10 in a plane just outboard the friction shoe carrier, Figure 9 a fragmentary vertical sectional view in a plane transverse to that of Figure 8 substantially as indicated by the line 9—9 of Figure 8, and Figure 10 a further fragmentary sectional view taken in the horizontal transverse plane indicated by the line 10—10 of Figure 8.

Figure 11 shows a further modification of the means of mounting the friction shoe supports.

My novel truck arrangement comprises a compression member 2, a tension member 4, merging at their ends as at 6 for connection to wheel connecting means (not shown) and connected intermediate their ends by spaced columns 8, 8, only one of which may be shown in the half side elevation of Figure 1. The tension and compression members and spaced columns define the usual central bolster opening 10 and over said bolster opening the compression member may have the box-section indicated at 12 in Figure 3, 15 while beneath said bolster opening the tension member may likewise have a box-section with a bottom chord 14, a top chord 16, inboard and outboard side walls 18 and 20 reinforced by triangular ribs 22, 22, said tension member section being further reinforced by the longitudinal central rib 24. The top web 16 of said tension member may be widened under said bolster opening to define the spring seat 25, and formed with upstanding inboard and outboard flanges 26 20 and 28, converging as at 30 and 32 (Figure 5) to merge with the inboard and outboard webs 34 and 36 of the adjacent column. Symmetrically seated on the spring seat 25, may be coil springs 38, 38, said springs diagrammatically indicated at 38, 38, said springs 45 being positioned on said seat by lugs 27, 27, upstanding from said seat. Said springs 38, 38 may be aligned along the inboard and outboard edges of said spring seat as best seen in the top plan view of Figure 5 in order to accommodate a friction device therebetween to be more particularly described hereafter.

Extending into the bolster opening 10 may be the end of the bolster generally designated 40, said bolster having a widened top portion with a shelf-like structure 42 at each side thereof,

said shelf-like structure having a depth A (Figure 1) less than the clearance B above the centrally disposed bolster guide flange 44 on the adjacent column so that said bolster may be projected into said opening above said column guide and placed in normal relationship therewith. The shelf portion 42 of the bolster has a side wall of generally arcuate contour as may best be seen at 46 in the top plan view of Figure 2, and centrally of said side wall is afforded a vertical slot 48 for reception of the beforementioned guide flange 44 on the adjacent column. The contour of the adjacent column is convex and complementary to the side wall of the bolster as may be noted at 50.

The end of the bolster 40 is of general box-section with a top wall 52, a bottom wall 54 with downwardly projecting spring positioning lugs 55, 55, a side wall 56, and a central vertical longitudinal flange 58. The bottom wall 54 is afforded a shallow transverse recess extending thereacross for reception of the base wall 60 of the interlocking casting generally designated 62, said interlocking casting having at each end thereof a vertical portion 64 with a side wall contour similar to that of the bolster and complementary to the guide surface on the adjacent column as may be noted at 66 in the top plan view of Figure 6. Each end portion 64 is formed with a flat inner face 68 which may abut as at 70 (Figure 1) the adjacent side wall 56 of the bolster, and said vertical portion 64 may be interlocked with said bolster side wall as by means of the vertical rib 72 receivable in the slot 74 at the side of the bolster (Figure 2). Centrally formed on the base wall 60 of the interlocking casting may be the raised lug 76 which may also be afforded interlocking engagement with the bolster as best seen at 78 in Figures 1 and 3.

Integrally formed as a part of the interlocking casting 62 is a friction housing 80 extending for substantially the length of said casting and depending from the base wall 60 thereof, said housing 80 comprising parallel side walls 82, 82, an intermediate wall 86, and end walls 88, 88 reinforced by the triangular ribs 90, 90 in line with the respective side walls 82, 82. The intermediate wall 86 may be cored away at its bottom end as best seen at 94 in the sectional view of Figure 3 and core openings may also be formed in the upper corners thereof as at 96, 96 for convenient foundry practice.

The friction housing 80 is open at its lower end, and said housing projects downwardly from the bottom of the interlocking casting 62 for cooperation with friction means supported from the tension member of the side frame. Said friction means comprises similar arrangements at respective ends of the housing 80, only one of which may be described. Each friction means comprises a plurality of friction shoe supports 98, 98 having bases 100, 100 recessed as at 102 in the top web of the tension member, each of said shoe supports having a vertical leg 104 projecting upwardly through an associated slot 106 in the retaining plate 108, also recessed in the top web of the tension member, and seated as at 110, 110 (Figures 3 and 4) on the shouldered edge of the recess at 102. The plate 108 has a top surface coplanar with the top surface of the web 16 of the tension member, said plate thus forming a portion of the area on which may be superposed the coil springs 38, 38 so that said coil springs serve to maintain said plate and said friction shoe supports in normal operating position. Chatter may

be avoided by utilizing a rubber pad 112 under the bases of the shoe support if desired, as illustrated in the sectional views of Figures 3 and 4. At the upper end of each friction shoe support 104 may be carried a friction shoe 114 having frictional engagement as at 116 with the adjacent side walls 82, 82 of the housing 80, and under compression between the opposed friction shoes 114, 114 may be the rubber pad 118 positioned with respect to said shoes as at 120, 120.

In this arrangement, each friction shoe 114 is relatively large and has one entire face in flat frictional engagement with the adjacent wall of the friction housing 80 and, inasmuch as four of such shoes are afforded, it will readily be seen that a large amount of friction can be developed if desired without undue wear. At the same time, the degree of friction developed may be controlled within reasonable limits by the character of the resilient member 118 compressed between opposed shoes.

In the modification illustrated in Figures 8, 9, and 10, the side frame structure may be generally similar to that of the previous modification and include the tension member 202 and the integral column 204 with the bolster guide lug 206 formed on the upper portion thereof, said tension member beneath the bolster opening 208 having a box-section with a bottom web 210, inboard and outboard walls 212 and 214, the intermediate longitudinal rib 216, and the top chord 218 reinforced by the upstanding inboard and outboard flanges 220 and 222, thus defining the spring seat 224 on which may be positioned a plurality of coil springs 226, 226 (Figure 10). Upstanding lugs 228, 228 may serve to position the respective coil springs, and additional positioning lugs 230, 230 may be formed on said spring seat intermediate adjacent coils, as best seen in the view of Figure 10.

As in the previous modification the top chord 218 of the tension member defining the spring seat may be recessed as at 232 for reception of the friction shoe retainer plate generally designated 234, said plate having a rectangular base, the top face of which may be flush with the spring seat 224 in order that the respective coils seat thereon as best illustrated in Figure 10. At each end of the retainer plate 234 and centrally positioned thereon may be the upstanding T-section lug 236 at opposite sides of which may be carried friction shoes 238, 238, each of said shoes being slotted at its lower end as at 240 for mounting on said lug 236. Each friction shoe may have secured thereto at its upper end a wear plate 242 which may have frictional engagement with the adjacent side wall 244 of the friction housing integrally formed as a part of the interlocking member as described in detail for the previous modification. Each pair of friction shoes 238, 238 may have on their opposed inner faces spring positioning means 246, 246, and between each pair of shoes may be confined a plurality of compression springs 248, 248 operative to urge the friction shoes into engagement with the friction surfaces of the adjacent side walls.

In this modification the integrally formed interlocking member and friction housing generally designated 250 is similar in form and function to that of the previous modification and comprises the base wall 252 and the upstanding end portions 254, 254 for interlocking engagement with the guide lugs 206, 206 on the respective columns of the side frame, said interlocking member 250 also comprising the upstanding cen-

tral lug 256 which may be interlocked with the bolster as described for the previous modification as well as the transverse rib 258 at each end thereof reinforcing the adjacent end portion 254 and also recessed in the lateral wall of the bolster also in manner described for the previous modification.

The depending friction housing, formed as an integral part of the member 250 may have the lateral walls thereof reinforced by spaced depending ribs 260, 260 and at the juncture of each rib with the base plate 252 may be formed spring positioning means 262, 262. Each end wall 264 of the friction housing may be cored away as at 266, 266 (Figure 8) to reduce the weight thereof. Similarly the base plate 252 may be cored away as at 268.

In Figure 11 I have illustrated a further slight modification wherein the box-section tension member 302 has a top chord 304 defining the spring seat 306 on which may be positioned resilient means as described for the previous modifications. As shown in Figure 11, the spring seat 306 may have integrally formed upstanding T-section lugs 308 at each side thereof on which may be positioned friction shoes fragmentarily indicated at 310, 310 in manner substantially identical to the showing of Figure 9 except that the upstanding lug in the modification in Figure 11 is integrally formed with the spring seat 306.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a truss side frame having tension and compression members and spaced columns defining a central bolster opening, a spring group on said tension member in said opening, a bolster extending into said opening in guiding engagement with said columns, an interlocking member associated with said bolster and in guiding engagement with said columns, said bolster and interlocking member being seated on said spring group, said interlocking member having integrally formed therewith depending walls with opposed friction surfaces, friction shoe supports having bases recessed in the top chord of said tension member, retaining means therefor, each of said supports having a vertical leg extending through said retaining means, friction shoes supported on said vertical legs in engagement with said opposed friction surfaces, and resilient means under compression between said friction shoes.

2. In a railway car truck, a truss side frame having tension and compression members and spaced columns defining a bolster opening, bolster guide means on each of said columns centrally thereof, a bolster extending into said opening with a widened shelf-like top portion in guiding engagement with said columns, and an interlocking member recessed in the bottom wall of said bolster and having upstanding ends cooperating with said shelf portion and also in guiding engagement with said columns, said interlocking member having integrally formed therewith spaced friction surfaces, means on said tension member supporting friction shoes for engagement with said surfaces respectively, and resilient

means under compression between the friction shoes in engagement with respective friction surfaces.

3. In a railway car truck, a side frame having a tension member and spaced columns defining in part a bolster opening, a spring group on said tension member, a bolster extending into said opening with a top shelf portion of restricted depth in guiding engagement with said columns, an interlocking member fixed to said bolster in cooperative engagement with said columns, said interlocking member having walls with opposed friction surfaces, means on said tension member supporting friction shoes in engagement with said surfaces, and a resilient pad under compression between said friction shoes, said top shelf portion having a depth less than the clearance between the bolster guide surfaces on said columns and the top of said bolster opening.

4. In a railway car truck, a side frame having tension and compression members and spaced columns defining a bolster opening, a spring seat on said tension member in said opening, a spring group thereon, a bolster extending into said opening in guiding engagement with said columns, an interlocking member cooperating with said bolster and said columns, said interlocking member and bolster being seated on said spring group, said spring group comprising springs aligned along the inboard and outboard edges of said seat, said interlocking member having friction walls depending between said inboard and outboard springs, friction shoe supports carried on said tension member, friction shoes resiliently supported therefrom in engagement with said friction surfaces, and resilient means under compression between said friction shoes.

5. In a railway car truck, a side frame having tension and compression members and spaced columns defining a bolster opening, a spring group on said tension member in said opening, a bolster extending into said opening in guiding engagement with said columns, an interlocking member associated with said bolster and in guiding engagement with said columns, said bolster and interlocking member being seated on said spring group, said interlocking member having a housing with opposed friction surfaces, means mounted on said tension member supporting friction shoes in engagement with the respective friction surfaces, and resilient means under compression between said shoes.

6. In a railway car truck, a truss side frame having tension and compression members and spaced columns defining a central bolster opening, a spring group on said tension member in said opening, a bolster extending into said opening in guiding engagement with said columns, an interlocking member associated with said bolster and in guiding engagement with said columns, said bolster and interlocking member being seated on said spring group, said interlocking member having integrally formed therewith depending walls with opposed friction surfaces, friction shoe supports carried on said tension member, friction shoes mounted on said supports in engagement with said friction surfaces, and resilient means under compression between said shoes.

7. In a railway car truck, a side frame having a tension member and spaced columns defining in part a bolster opening, a spring group on said tension member, a bolster extending into said opening with a top shelf portion of restricted depth in guiding engagement with said columns,

an interlocking member fixed to said bolster in cooperative engagement with said columns, said interlocking member having means with opposed friction surfaces, and means on said tension member supporting friction shoes in engagement with said surfaces, said top shelf portion having a depth less than the clearance between the bolster guide surfaces on said columns and the top of said bolster opening.

8. In a railway car truck, a side frame having tension and compression members and spaced columns defining a bolster opening, a spring seat on said tension member in said opening, a spring group thereon, a bolster extending into said opening in guiding engagement with said columns, an interlocking member cooperating with said bolster and said columns, said interlocking member and bolster being seated on said spring group, said spring group comprising springs aligned along the inboard and outboard edges of said seat, said interlocking member having friction walls depending between said inboard and outboard springs, friction shoe supports carried on said tension member, and friction shoes supported therefrom in engagement with said friction surfaces.

9. In a railway car truck, a truss side frame having tension and compression members and spaced columns defining a bolster opening, bolster guide means on each of said columns centrally thereof, a bolster extending into said opening with a widened shelf-like top portion in guiding engagement with said columns, and an interlocking member recessed in the bottom wall of said bolster and having upstanding ends cooperating with said shelf portion and also in guiding engagement with said columns, said interlocking member having depending spaced friction surfaces, and means on said tension member supporting friction shoes for engagement with said surfaces respectively.

10. In a railway car truck, a side frame having tension and compression members and spaced columns defining a bolster opening, a spring group on said tension member in said opening, a bolster extending into said opening in guiding engagement with said columns, an interlocking member associated with said bolster and in guiding engagement with said columns, said bolster and interlocking member being seated on said spring group, said interlocking member having depending means with opposed friction surfaces, and means mounted on said tension member supporting friction shoes in engagement with the respective friction surfaces.

11. In a railway car truck, a truss side frame having tension and compression members and spaced columns defining a central bolster opening, a spring group on said tension member in said opening, a bolster extending into said opening in guiding engagement with said columns, an interlocking member associated with said bolster and in guiding engagement with said columns, said bolster and interlocking member being seated on said spring group, said interlocking member having walls with opposed friction surfaces, friction shoe supports carried on said tension member, and friction shoes mounted on said supports in engagement with said friction surfaces.

12. In a car truck, a truss side frame having a central bolster opening, a spring group on said side frame, a bolster seated on said spring group in said opening in cooperative engagement with said frame, and a member fixed to said bolster

for interlocking said side frame and bolster, said interlocking member having spaced depending walls, friction surfaces on each of said walls, friction shoe support means carried on said frame, friction shoes mounted on said support means in engagement with said friction surfaces, said friction shoes being mounted in pairs with the respective shoes of each pair in opposed relationship to each other, and resilient means under compression between the shoes of each pair.

10 13. In a railway car truck, a side frame having tension and compression members and spaced columns defining a bolster opening, bolster guide means centrally positioned on said columns, a spring seat on said tension member in said opening, a spring group thereon, said spring group comprising springs aligned along the inboard and outboard edges of said seat, a bolster extending into said opening in guiding engagement with said columns, an interlocking member secured to said bolster in cooperative engagement with said columns, said interlocking member having integrally formed spaced friction surfaces, means on said tension member supporting friction shoes in engagement with said surfaces, and a resilient member under compression between said shoes.

15 14. In a railway car truck, a side frame having a tension member and spaced columns defining in part a bolster opening, a spring group on said tension member, a bolster extending into said opening with a top shelf portion of restricted depth in guiding engagement with said columns, an interlocking member secured to the bolster in cooperative engagement with said columns, said interlocking member having walls with opposed friction surfaces, means on said tension member supporting friction shoes in engagement with said surfaces, and resilient means under compression between said friction shoes.

20 15. In a railway car truck, a side frame having tension and compression members and spaced columns defining a bolster opening, bolster guide means centrally positioned on said columns, a spring seat on said tension member in said opening, a spring group thereon, said spring group comprising springs aligned along the inboard and outboard edges of said seat, a bolster extending into said opening in guiding engagement with said columns, an interlocking member fixed to said bolster in cooperative engagement with said columns, said interlocking member having integrally formed spaced friction surfaces, and means on said tension member supporting friction shoes in engagement with said surfaces.

25 16. In a railway car truck, a side frame having a tension member and spaced columns defining in part a bolster opening, a spring group on said tension member, a bolster extending into said opening with a top shelf portion of restricted depth in guiding engagement with said columns, an interlocking member secured to said bolster in cooperative engagement with said columns, said interlocking member having depending walls with opposed friction surfaces, and means on said tension member supporting friction shoes in engagement with said surfaces.

30 17. In a car truck, a truss side frame having a central bolster opening, a spring group on said side frame, a bolster seated on said spring group in said opening in cooperative engagement with said frame, a member secured to said bolster for interlocking said side frame and bolster, said interlocking member having depending walls with opposed friction surfaces, means mounted on said side frame supporting friction shoes in engage-

ment with said surfaces, and a resilient pad under compression between said shoes.

18. In a railway car truck, a side frame comprising a bolster opening, a spring group on said frame in said opening, a bolster supported on said spring group, and a friction absorbing device beneath said bolster and comprising followers supported from said frame and said bolster respectively, and friction shoes supported by one of said followers and resiliently urged into engagement with the other, one of said followers having a wall recessed in said bolster and affording a seat coplanar with the bottom wall thereof for abutment of said spring group, said spring group affording the sole means of retaining said last-mentioned follower in normal relationship with said bolster.

19. In a railway car truck, a side frame comprising a bolster opening, a spring group on said frame in said opening, a bolster supported on said spring group, and a friction absorbing device comprising followers supported from said frame and said bolster respectively, and friction shoes supported by one of said followers in engagement with the other, at least one of said followers being partially recessed in its supporting member and with said member affording a coplanar seat for one end of said spring group, said spring group acting to retain said last-mentioned follower and its supporting member in normal relationship.

20. In a railway car truck, a side frame member comprising a bolster opening, resilient means on said member in said opening, a bolster member supported on said means, a follower comprising spaced friction walls supported beneath said bolster member from one of said members, follower stems each comprising a base recessed in the other member, a retaining plate recessed in the last mentioned member and comprising slots therethrough, said follower stems projecting through said slots, friction means on said stems in engagement with respective walls, and resilient means urging said friction means into said engagement.

21. In a railway car truck, a side frame member comprising a bolster opening, resilient means on said member in said opening, a bolster member supported on said means, a follower comprising spaced friction walls supported beneath said bolster member from one of said members, follower stems each comprising a base recessed in the other member, a retaining plate recessed in the last mentioned member and comprising slots therethrough, said follower stems projecting through said slots, friction means on said stems in engagement with respective walls, a resilient pad compressed between said bases and the associated member, and resilient means urging said friction means into said engagement.

22. In a railway car truck, a frame member comprising a bolster opening, resilient means on said frame member in said opening, a bolster member supported on said means, a follower comprising spaced friction walls supported beneath said bolster member from one of said members, follower stems each comprising a base recessed in the other member, means retaining said bases in assembly and permitting restricted movement thereof with respect to the associated member, friction means on said stems in engagement with respective walls, and resilient means urging said friction means into said engagement.

23. In a railway car truck, a frame member comprising a bolster opening, resilient means on said frame member in said opening, a bolster member supported on said means, a follower associated with one of said members and comprising spaced friction walls beneath the bolster member, a T-shaped follower associated with the other of said members, friction shoes comprising openings slidably receiving the respective horizontal flanges of said T-shaped follower, and resilient means under compression between said shoes for urging them into engagement with respective walls.

24. In a railway car truck, a side frame comprising a bolster opening, a group of springs on said frame in said opening, a bolster supported on said group, and a friction absorbing device comprising a follower having a web recessed in the bottom wall of said bolster and affording a surface coplanar with the bottom of said wall for abutment of said group, said springs being seated partially against said surface and partially against said wall, and friction means supported from said frame in frictional engagement with said follower.

25. In a railway car truck, a side frame having spaced columns at opposite sides of a bolster opening, a group of springs on said frame in said opening, a bolster supported on said group, and a friction absorbing device comprising a follower having a web recessed in the bottom wall of said bolster and affording a surface coplanar with the bottom of said wall for abutment of said group, said springs being seated partially against said surface and partially against said wall, and friction means supported from said frame in engagement with said follower, portions of said follower being interlocked with said columns.

26. In a railway car truck, a side frame having spaced columns at opposite sides of a bolster opening, a spring group on said frame in said opening, a bolster supported on said group, and a friction absorbing device beneath said bolster and comprising followers supported respectively from said frame and said bolster, and friction shoes supported by one of said followers and resiliently urged into engagement with the other, one of said followers having a wall recessed in said bolster affording a seat coplanar with the bottom wall thereof for abutment of said group, said spring group affording the sole means of retaining said last-mentioned follower in normal relationship with said bolster, at least one of said followers having interlocking engagement with said columns.

27. In a railway car truck, a side frame comprising spaced columns defining in part a bolster opening, a spring group on said frame in said opening, a bolster supported on said group, and a friction absorbing device comprising followers supported respectively from said frame and said bolster, and friction shoes supported by one of said followers in engagement with the other, at least one of said followers being partially recessed in its supporting member and with said member affording a coplanar seat for one end of said group, said spring group acting to retain said last-mentioned follower and its supporting member in normal relationship, and at least one of said followers having an interlock with said columns.

ROBERT B. COTTRELL.
